JEWELRY CHAIN

Paul Bardach, Providence, R. I.

Application November 26, 1949, Serial No. 6,272

Term of patent 3½ years

(Cl. D45—16)

To all whom it may concern:

Be it known that I, Paul Bardach, a citizen of the United States, residing at Providence, in the county of Providence and State of Rhode Island, have invented a new, original, and ornamental Design for a Jewelry Chain, of which the following is a specification, reference being had to the accompanying drawing, constituting a part hereof.

Fig. 1 is a top plan view of a jewelry chain, showing my new design;

Fig. 2 is a side elevational view thereof; and

Fig. 3 is an enlarged end view of one of the links of the chain.

I claim:

The ornamental design for a jewelry chain, substantially as shown.

PAUL BARDACH.
